UNITED STATES PATENT OFFICE.

WILLIAM W. LASKER, OF BROOKLYN, NEW YORK, ASSIGNOR TO POWERS ACCOUNTING MACHINE CORPORATION, OF NEW YORK, N. Y., A CORPORATION OF DELAWARE.

RIBBON-FEED MECHANISM.

Application filed December 18, 1923. Serial No. 681,335.

To all whom it may concern:

Be it known that I, WILLIAM W. LASKER, a citizen of the United States, and a resident of Brooklyn, New York, have invented certain new and useful Improvements in Ribbon-Fee Mechanism, of which the following is a specification.

My invention relates to printing tabulating machines, and in particular relates to means for effecting the feed of the type ribbon which is used in such machines.

Printing tabulating machines such as are used for tabulating the data from punched cards frequently are so built that the operator can cause the machine either to tabulate each item together with the totals, or cause the machine to print the totals only. With such machines it is customary to have the type ribbon advance for each operation, irrespective of whether the machine is printing or not. Specifically, my invention relates to a mechanism whereby the ribbon advancing gear in such machines is connected with the print control mechanism by cut-out gear, so that if the printing hammers are held so that they do not tabulate each item, the ribbon will not advance except when a total is taken; on the other hand, if the machine is set so that each item is printed, the ribbon will advance for each item. In other words, the ribbon advances only when printing is being done.

In the illustrative example of my invention described in detail in the present specification I show the invention applied to such a tabulating machine, but I do not illustrate all of the parts of such machine, as the same do not form part of the present invention, except to such extent as they cooperate with the ribbon control mechanism.

An illustrative example of a device embodying my invention together with the co-operating parts of the tabulating machine is shown in the accompanying drawings, in which Fig. 1 is an end view, with certain parts broken away, better to show the construction. Fig. 2 is a section on line 2—2 of Fig. 1, but showing the ribbon driving mechanism in a different position from Fig. 1. Fig. 3 is a section on line 3—3 of Fig. 4, and Fig. 4 is a section on line 4—4 of Fig. 3.

Referring to the drawings, 10 is shaft forming part of the regular tabulating mechanism which controls the operation of the printing hammers (not shown). When this

shaft is in the position illustrated in Fig. 1, the printing hammers are allowed to operate. This shaft is under spring tension by a spring not shown, which tends to cause the shaft to rotate in a clockwise direction for about 15 degrees from the position shown. When the shaft 10 has thus rotated, the printing hammers are locked so that they cannot operate. This is well understood in the art, and therefore the detailed mechanism for accomplishing this result is not described in the present specification.

In order to control the position of shaft 10, and thus to control the operation of the printing hammers, there is fixed on shaft 10 an arm 11 carrying a pin 12. The hammer release lever 13 is pivoted to the main frame at 14 and has its upper end adapted to cooperate with pin 12, and at its lower end is bent over to form a plate 15, which contacts with pin 16. The pin 16 is under pressure from spring 17 which tends to cause the pin to move into the position shown in dotted lines in Fig. 1, but this pin can be held in position shown in full lines in Fig. 1 by pin 18 which engages with a catch member 19. When pin 16 is locked in the position shown in full lines in Fig. 1, shaft 10 is likewise held in the position shown in Fig. 1 and the printing hammers will operate. When pin 16 is allowed to return to the position shown in dotted lines in Fig. 1, lever 13, under usual conditions, oscillates and permits shaft 10 to rotate into the non-print position. If the operator wishes to have each item tabulated, pin 16 is fixed in the position shown in full lines in Fig. 1; if each item is not to be tabulated, pin 16 is allowed to move out to the position shown in dotted lines.

It is of course necessary that when a total is taken, the printing hammers be allowed to function independent of the setting of pin 16. The manner in which this is accomplished is shown in Fig. 1, in which the parts are illustrated in the position which they assume when a total is being taken. Shaft 20 which, in operation, rocks through an arc of about 30 degrees, is shown as rotated to its extreme counter-clockwise position. Attached to the shaft 20 is an arm 21 to which is pivoted the total connecting link 22. Link 22 is connected to the total taking mechanism (not shown) in such a way that when a total is being taken

this link is held in the position shown in Fig. 1. After the total has been taken, this link moves to the right a distance equal to the movement permitted in pin 16. Screwed to the link 22 is a bracket 23, which has an extension 24 which contacts with lever 13 and by oscillating this lever moves shaft 10 into the printing position. With the total mechanism in the position shown in Fig. 1, the printing hammers will operate, irrespective of the setting of pin 16. However, the totalling parts are in this position only when a total is being taken and under normal tabulating conditions the extension 24 of bracket 23 is clear of lever 13.

The parts thus far described relate primarily to the printing tabulating machine itself, and except as they cooperate with the ribbon release mechanism, form no part of the present invention.

In order to control the movement of the ribbon, I provide a lever 25 which contacts with lever 13. The lever 25 is connected with a plate 26, or it may be integral with the plate 26 which is pivoted to a bracket 27, and which contacts with the upper end of a pin 28. Pin 28 in turn contacts with an arm 29 which is fixed on a shaft 30. A spring 31 tends to raise the free end of arm 29 and thus to lift pin 28. In Fig. 1 pin 28 is shown in depressed position, resulting from pressure exerted on lever 25 by lever 13, which pressure is transmitted through plate 26 to pin 28. Shaft 30 extends part way across the front of the tabulating machine and about the middle of the machine has projecting from it two arms 32 and 33. These arms respectively lie above spring plates 34 and 35, the tension of which is upward. The tension of spring plates 34 and 35 is adjusted in relation to the tension of spring 31, so that when the parts of the mechanism are in the non-print position, arms 32 and 33 will depress spring plates 34 and 35. However, when arm 29 is depressed, arms 32 and 33 are lifted and spring plates 34 and 35 are allowed to assume the position shown in Fig. 2. Attached to the main rock-shaft 36 of the tabulating mechanism (see Figs. 3 and 4) is an arm 37 and pivoted on shaft 36 is an arm 38. Screw 39 passes through a slot 40 in arm 37 and causes arm 38 to follow part of the movement of arm 37. Shaft 36 rocks through an angular movement of 60° but because screw 39 moves in slot 40, arm 38 will move through an angular movement of considerably less than 60° . Pivoted to arm 38 are a pair of segmental racks 41 and 42. Rack 41 is so positioned that it is pushed upward by spring plate 34 and rack 42 is similarly pushed up by spring plate 35; but the extent to which these racks are pushed up will depend upon the position of spring plates 34 and 35. Adapted to cooperate with rack

41 is a ratchet gear 43 mounted on a shaft 44 which is connected by a bevel gear 45 with shaft 46, at the top of which is fixed a ribbon spool 47. A ratchet gear 48, similar to gear 43, is adapted to cooperate with rack 42 and is attached to a shaft 49 which is connected with the other ribbon spool not shown in the drawing. When shaft 10 is held in the printing position, one or the other of racks 41 or 42 is held by spring plates 34 or 35 pressed against the corresponding gears 43 or 48 with a yielding pressure, so that reciprocating movement of the rack will cause its ratchet gear to rotate in one direction. However, when lever 13 moves to release shaft 10, and thus to lock the printing hammers, shaft 30 is rocked by spring 31 and spring plates 34 and 35 are depressed by arms 32 and 33, so that racks 41 and 42 are permitted to drop clear of gears 43 and 48. In other words, the ribbon driving mechanism is directly connected with the print control mechanism and the ribbon is only advanced after each printing operation.

Obviously, it is not feasible to drive both ribbon spools at once, so I supply mechanism that will disconnect either rack 41 or 42 from its corresponding gear. This mechanism comprises the bar 49' (to which spring plates 34 and 35 are attached) which carries a cam block 50. In Fig. 2 cam block 50 is shown in position where it will hold rack 42 clear of the gear 48 and rack 41 is in position to cause gear 43 to rotate a part of one turn for each oscillation of mainshaft 36, so that the ribbon will be wound on spool 47. If bar 49' is moved to the left, rack 42 will be allowed to engage with gear 48 and rack 41 will be held clear of gear 43, so that the ribbon will be unwound from spool 47.

In Fig. 1, the parts are shown in the position where the ribbon is being unwound from spool 47, just before the movement of the spools is reversed to the position shown in Fig. 2. In order to accomplish the reversal, I use the pin 51 which, as is well understood in the art, is held by spring tension away from the center of spool 47 but is drawn toward the center by the tension of the ribbon. When the ribbon is substantially all unwound from spool 47, pin 51 springs out to the position shown in Fig. 1 and on the next rotation this pin will strike the reverse lever 52. The lower end of the reverse lever 52 strikes arm 53 on shaft 54. Extending from shaft 54 is arm 55 which is connected with bar 49 in such a way that when pin 51 strikes the upper end of lever 52, bar 49 is pushed into the position shown in Fig. 2 and immediately spool 47 will be driven positively and will start to wind up the ribbon.

It is to be understood that the foregoing example is given for purposes of illustration

only, and it is not intended that my claims shall be limited to the exact construction shown, for those skilled in the art will readily be able to modify the construction in 5 many details without departing from the spirit of my invention.

What I claim is:

1. A tabulating machine having printing mechanism for tabulating and taking totals 10 and having printing control mechanism whereby the machine may be set either to tabulate each item and print the totals, or to print the totals only, in combination with mechanism for advancing the type ribbon, 15 and cut-out mechanism operatively connected with said printing control mechanism and with the mechanism for advancing the type ribbon, so that the ribbon will be advanced only when the printing mechanism is in 20 operative position.

2. A structure as defined in claim 1, in which the mechanism for advancing the type ribbon comprises a shaft operatively connected with a ribbon spool and positively 25 driven means for causing such shaft to rotate intermittently, and in which the cut-out mechanism comprises means for disconnecting such positively driven means from such shaft when the printing mechanism is not in 30 operative position.

3. A structure as defined in claim 1, in which the mechanism for advancing the type ribbon comprises a shaft operatively connected with a ribbon spool, a gear on said 35 shaft, and positively driven means for caus-

ing said shaft to rotate intermittently, comprising a segmental rack pivoted so that it can be moved in and out of engagement with said gear.

4. A device as defined in claim 1, in which 40 the mechanism for advancing the type ribbon comprises two shafts, each operatively connected with a ribbon spool and positive means for causing such shafts to rotate together with automatic means operated by the 45 ribbon for disconnecting such means from one shaft and connecting such means with the other shaft, and in which the cut-out mechanism comprises means for disconnecting such positively driven means from both 50 shafts when the printing mechanism is not in operative position.

5. A device as defined in claim 1, in which the mechanism for advancing the type ribbon comprises two shafts, a gear on each of 55 said shafts, means for operatively connecting each of said shafts with a ribbon spool, positively driven means for causing such shafts to rotate, comprising a pair of segmental racks pivoted so that each can separately be moved in and out of engagement with one of said gears, automatic means operated by the ribbon for disconnecting one of said racks from one of said gears and connecting the other of said racks with the other 60 of said gears, said device likewise comprising means whereby such racks can simultaneously be caused to move away from said gears. 65

WILLIAM W. LASKER.
